UNITED STATES PATENT OFFICE.

DWIGHT S. CLARK, OF ROCHESTER, NEW YORK, ASSIGNOR TO THE STECHER LITHOGRAPHIC COMPANY, OF SAME PLACE.

PAPER BOX.

SPECIFICATION forming part of Letters Patent No. 513,760, dated January 30, 1894.

Application filed October 7, 1893. Serial No. 487,456. (No model.)

To all whom it may concern:

Be it known that I, DWIGHT S. CLARK, of Rochester, in the county of Monroe and State of New York, have invented certain new and 5 useful Improvements in Paper Boxes; and I do hereby declare the following to be a full, clear, and exact description of the same, reference being had to the accompanying drawings, forming a part of this specification, and 10 to the reference-numerals and letters of reference marked thereon.

My present invention has for its object to provide an improved collapsible paper-box or carton adapted for holding merchandise of 15 various kinds, or bottles containing medicines or the like, and it consists in certain improvements in construction and combinations of parts, all as will be hereinafter fully described and the novel features pointed out particularly in the claims at the end of this specification.

In the accompanying drawings: Figure 1 is a plan view of the blank; Fig. 2, a perspective view showing the first stage of folding 25 one end; Fig. 3, a similar view of another stage; Fig. 4, a perspective view showing the manner of folding the other end of the box or carton; Fig. 5, a view of a modification.

Similar reference numerals and letters of 30 reference in the several figures indicate similar parts.

In making boxes or cartons, it is often-times desirable to provide them at one end with a tight closure, which may be secured by 35 pasting down a single covering flap forming one end of the box, while the other end is capable of being secured and covered by a label or other separate covering piece, which must be broken in opening the box or case, and 40 also this kind of a fastening is considerably cheaper than where a long covering flap is employed, effecting a saving in the material of which the box is composed, inasmuch as it is not necessary to have three or four long 45 flaps overlapping each other, which would be necessary to form a tight closure.

The blank of which my improved box is constructed is shown in plan view in Fig. 1 made of a single piece of cardboard, or similar material, the full lines indicating the

places where the blank is cut, and the dotted lines where it is scored or indented in such manner that it may be readily folded. The blank is preferably divided by the scored lines 3, 4 and 5 into the panels *a*, *b*, *c*, and *d*, 55 the panel *a* having a short securing strip *e* attached thereto, as shown. The blank is further scored on the lines 1 and 2 indicating the top and bottom of the box or carton when set up, and at the end of the panel *a* is formed 60 a broad covering flap *a'*; at the end of *b*, the flap *b'* is formed with the tongue 6 and scored to form a triangular panel 7; at the end of the panel *c* is formed the flap *c'* scored to form the triangular panels 8 and 9, and at the 65 one end of the panel *d* is a flap *d'* scored to form the triangular panel 10, said flap *d'* being also provided with a cut tongue 11; these parts forming the closure for the end of the box, which is adapted to be sealed when the 70 box is set up.

In order to set up the box, the blank is bent on the lines 3, 4 and 5, the panel *d* and strip *e* are pasted together, as is usual in this class of devices, and then in order to secure the 75 end just described, the triangular panels or gores 7, 8, 9 and 10 are bent inward, as shown in Fig. 2, and closed down, bending the flaps *c'*, *d'*, first, and then the flap *b'* and inserting the tongue 6 on the latter into the aperture 80 in the flap *d'* formed by cutting the tongue 11 therein, as shown in Fig. 3. This will leave the broad flap *a'* standing, and the flaps *b'*, *c'*, and *d'* will constitute a flat surface to which paste or glue may be applied, and then 85 the flap *a'* may be turned down and secured thereto making a secure and flat fastening, as will be understood, and the flat surface formed by these flaps *b'*, *c'*, and *d'* will afford a secure holding ground for the flap *a'*. 90

Instead of cutting the tongue 11 in the flap *d'*, it will be understood that a single slit would answer the purpose, although this would render it more difficult to enter the tongue 6 in it, and I therefore prefer the construction shown. 95

Although this box is adapted, as stated, to have one end closed by a separate label at the other end from the one described, it will be understood that the fastening just de- 100

scribed could be applied to either or both ends, if desired. In the preferred form, however, in which the fastening label is employed and a tight closure is not desired at 5 the other end, the blank is constructed and the closure formed as in Figs. 1 and 4, the panels *a* and *c* being provided at one end with the flaps *a*² and *c*², both similarly constructed with tongues 12 formed by slitting the mate- 10 rial, as shown, and the panels *b* and *d* are provided with flaps *b*² and *d*², each of which is cut so as to form tongues 13, which, however, are only for the purpose of providing slits for the accommodation of the tongues 15 12 on the flaps *a*² and *c*². In closing this end of the box the flaps *b*² and *d*² are first folded down, as indicated in Fig. 4, and then the flaps *a*² and *c*² are folded over upon them and the tongues 12 inserted in the slits formed 20 in cutting the tongues 13. This form of fastening is not sufficiently tight for packages of pulverulent material, but might be used for packages containing bottles or similar articles and could be used, of course, without 25 employing the form of closure shown at the other end of the box, but is well adapted to a form of box which it is desired to close at one or both ends, with a label or covering piece, as will be understood by those skilled 30 in the art.

It will be noted that the flaps *b*', *c*', and *d*' are formed integral and that only scored lines separate them, the flap *a*' being the only one that is separate, so that a better closure 35 is formed and one less liable to permit the escape of a pulverulent material than a closure employing separate flaps, also that the flaps *b*', *c*' and *d*' are supported in a measure by the gores 7, 8, 9 and 10, thereby allowing the 40 flap *a*' to be more securely fastened. It will also be understood that the upper part of the

flap *b*' containing the tongue 6 could be dispensed with, if desired, and the flap *b*' made the same height as the flaps *c*' and *d*', and when this form is used a flat surface for the 45 securing of the broad flap *a*' would be obtained without the necessity of performing a tongue-and-slit locking operation, all as shown in Fig. 5.

I claim as my invention—

1. The herein described closure for folding boxes embodying the flaps *b*', *c*', and *d*' scored to form panels 7, 8, 9 and 10, the interlocking tongue and slot connections between flaps *b*' and *d*', and the separate whole flap *a*', ar- 55 ranged and operating substantially as de- scribed.

2. A blank for folding boxes having the panels *a*, *b*, *c*, *d* and a connecting flap and also having flaps *a*', *b*', *c*', and *d*', the three latter 60 scored to form panels 7, 8, 9 and 10, and the flaps *b*' and *d*' having the interlocking portions 6 and 11, substantially as described.

3. The herein described blank for folding boxes consisting of the panels *a*, *b*, *c*, *d*, the 65 flap *a*', and the flaps *b*', *c*', *d*' scored to form panels 7, 8, 9 and 10, interlocking tongues and slits between the flaps *b*' and *d*', and short flaps *a*², *b*², *c*², *d*² at the other end of the blank having interlocking tongues and slots 12 and 70 13, substantially as described.

4. The herein described closure for folding boxes embodying the flaps *b*', *c*' and *d*' scored to form panels 7, 8, 9 and 10, and the flap *a*' broader than the other flaps, and adapted to 75 cover them all when folded, substantially as shown and described.

DWIGHT S. CLARK.
